UNITED STATES PATENT OFFICE.

THOMAS P. HIGGINS AND WILLIAM McDERMOTT, OF NEW BRIGHTON, NEW YORK.

DRY-PIPE VALVE.

1,161,671.

Specification of Letters Patent.

Patented Nov. 23, 1915.

Application filed August 19, 1915. Serial No. 46,270.

To all whom it may concern:

Be it known that we, THOMAS P. HIGGINS and WILLIAM McDERMOTT, citizens of the United States, residing at New Brighton, in the county of Richmond, State of New York, have invented a new and useful Dry-Pipe Valve; and we do hereby declare the following to be a full, clear, and exact description of the invention, such as will enable others skilled in the art to which it appertains to make and use the same.

This invention relates to the art of valves, and particularly to an improved dry pipe valve designed for use in connection with sprinkler systems, and for all other purposes for which a dry pipe valve can be used.

One of the objects of the invention is the provision of an improved valve to be located in the piping of a sprinkler system between the water and the spreader or sprayer or sprinkler of the system, there being a pressure of air between the valve and the sprayer, spreader, or sprinkler, so that when the sprinkler is opened, the air pressure will be released, which releases the valve allowing its spring to open the valve, so that the inflow of water will pass to and through the sprinkler and at the same time sound an electrical fire alarm.

In practical fields the details of construction may necessitate alterations, falling within the scope of what is claimed.

The invention comprises further features and combination of parts, as hereinafter set forth, shown in the drawings and claimed.

In the drawings: Figure 1 is a vertical sectional view through the valve constructed in accordance with the invention. Fig. 2 is a transverse sectional view on line 2—2 of Fig. 1. Fig. 3 is an enlarged detail view of the oscillatory clapper arm or member.

Referring to the drawings, 1 designates a valve casing having a water chamber 2, and the two air chambers 3 and 4, and the alarm chamber 5. The air chambers 3 and 4 communicate with each other by way of the passage 6, transversely of which a pin or shaft 7 extends, which pin is mounted in suitable bearings 8 of the casing of the valve. The water supply pipe (not shown) is designed to be connected to the casing 1 by means of the flange 9, through the apertures or openings 10 of which, the bolts (not shown) of said supply pipe are designed to pass. The wall 50 of the casing 1 of the valve has an opening 11, for draining the valve, which opening 11

is closed by the provision of a threaded plug 12. The wall 13 dividing the air chamber 3 from the water chamber 2 has an opening 14, and this wall 13 constitutes a seat 15 for the disk valve 16, for closing the opening 14. A pipe 17 which connects to the sprinkler or spreader (not shown) of the sprinkler system (not shown) communicates with the air chamber 3, owing to said pipe 17 being bolted at 18 to the valve casing. Access may be had to the chambers 3 and 4 through the openings 19 and 20, which are closed by the plates 21 and 22, bolted to the casing 1 by the bolts 23 and 23^a. Access may be had to the alarm chamber 5 by way of the opening 24, which is closed by the plate 25 secured to the casing 1 of the valve by the bolts 26. Access to said chambers is made possible in this manner, for the purpose of cleaning the chambers, or for the purpose of repairs or the like when desired. The wall 27 between the alarm chamber 5 and the air chamber 4 has an opening 28, and the under surface of the wall 27 constitutes a valve seat for the disk valve 30, for closing communication between the alarm chamber and the air chamber 4, that is, when the air is in the chambers 3 and 4 and in the pipe 17 between the sprinkler, spreader or sprayer, and the valve. Air is held in said pipe 17 between the sprinkler (not shown) and the valve, owing to the sprinkler being closed by any suitable sealing means, and when the sealing means (not shown) is destroyed by fire, the air pressure between the sprinkler and the valve is released. Pivotaly mounted on the pin 7 is an oscillating member or clapper arm 32, to the arm 33 of which the disk valve 16 is connected by the threaded lug 34 having lock nuts 35. To the arm 36 of said clapper member the disk valve 30 is likewise connected by the threaded lug 37 and lock nuts 38.

The clapper member has an enlarged cylindrical part 39; where it is pivotaly mounted upon the pin 7, and which cylindrical part is hollowed out as shown at 40, to receive the coil spring 41, which surrounds the pin 7. One end 42 of the coil spring 41 engages the upper face of the arm 36, while the other end 43 engages the under face of the wall 27 of the valve casing, in which case the tendency of the spring is to oscillate the clapper member 32 to the position shown in dotted lines, that is, when the air pressure in the pipe 17 and the air

chambers 3 and 4 is broken, and in this case the water will rush into the chambers 3 and 4, and into the alarm chamber 5 (closing the circuit of the alarm mechanism (not shown) 5 thereby setting off the fire alarm), and thence through the pipe 17 to and out through the sprinkler, spreader or sprayer, thereby assisting in putting out the fire. Slidably mounted in a socket 45 of the 10 chamber 3 is an abutment member 46, held outwardly as shown in full lines by the tension of the springs 47, and when the clapper member is thrown open by the tension of its spring, the arm 33 of said member will 15 contact with the abutment member 46, so as to be limited to the position shown in dotted lines. A terminal plug 50 is arranged in the upper wall of the alarm chamber 5, to make electrical connections (not shown) 20 with a fire alarm (not shown) and a circuit closer (not shown) designed to be placed in the chamber 5, and when communication is had between the chambers 4 and 5, that is, when the clapper member is thrown in the 25 position as shown in dotted lines, the water being an electrical conductor will close the circuit (referred to hereinbefore) of the fire alarm, thereby sounding the alarm. A ring 31 is carried by the upper face of the disk 30 valve 30, for setting the valve and the clapper member. A tube 52 is threaded at 53 into the casing adjacent the alarm chamber 5 and has a ball valve 53^a coöperating with its seat 54 to close the valve opening 55, so 35 that when the water rushes into the alarm chamber 5 to close the circuit, the pressure of the water will close the ball valve 53^a, thereby preventing any slight leakage to the alarm chamber.

40 The invention having been set forth, what is claimed as new and useful is:—

1. In a valve as set forth, a casing having two air chambers in communication with each other, an alarm chamber having a port 45 for communication with one of the air chambers, a water chamber having a port for communication with the other air chamber, an oscillatory member having valves adapted for closing said ports of communication 50 between the alarm chamber and one air chamber, and the water chamber and the other air chamber under air pressure in the two air chambers.

55 2. In a valve as set forth, a casing having two air chambers in communication with each other, an alarm chamber having a port for communication with one of the air chambers, a water chamber having a port

for communication with the other air chamber, an oscillatory member having valves 60 adapted for closing said ports of communication between the alarm chamber and one air chamber, and the water chamber and the other air chamber under air pressure in the two air chambers, and means for oscillating 65 said member to open said valves when said air pressure in said air chambers is released.

3. In a valve as set forth, a casing having two air chambers in communication with each other, an alarm chamber having a port for communication with one of the air chambers, a water chamber having a port for communication with the other air chamber, an oscillatory member having valves 70 adapted for closing said ports of communication between the alarm chamber and one air chamber, and the water chamber and the other air chamber under air pressure in the two air chambers, and means for oscillating 75 said member to open said valves when said air pressure in said air chambers is released, and abutment means in one of the air chambers to limit the oscillatory movement of said member.

4. In a valve as set forth, a casing having two air chambers in communication with each other, a pin extending transversely of the communication between the two chambers, an alarm chamber having a port for communication with one air chamber, a water chamber having a port for communication with the other air chamber, a clapper member pivotally mounted upon said pin having disk valves at both ends for closing 80 said ports of communication between the alarm chamber and one air chamber and the water chamber and the other air chamber, when air pressure is held in said air chambers, said clapper member, where it is pivoted upon the pin being hollowed 85 out, a spring in said hollowed out portion of the clapper member and coiled about the pin, for oscillating the clapper member to open said valves, when the air pressure is released in said air chambers, and an abutment member in one of the air chambers to limit the clapper member in its oscillatory movement.

In testimony whereof we have signed our names to this specification in the presence 110 of two subscribing witnesses.
